UNITED STATES PATENT OFFICE.

JAMES WILSON, OF JAMESTOWN, NEW YORK, ASSIGNOR TO SALISBURY BALL BEARING CORPORATION, A CORPORATION OF NEW YORK.

CHUCK.

1,285,866.

Specification of Letters Patent.

Patented Nov. 26, 1918.

Application filed June 22, 1917. Serial No. 176,305.

To all whom it may concern:

Be it known that I, JAMES WILSON, a subject of the King of Great Britain, residing at Jamestown, in the county of Chautauqua and State of New York, have invented certain new and useful Improvements in Chucks, of which the following is a specification, reference being had therein to the accompanying drawing.

10 This invention relates to improvements in chucks, the same being especially adapted and constructed for use in holding the race-way rings of ball bearings in such a manner as to permit the grinding and truing thereof, one object of the invention being the provision of a mechanism by means of which the bearing ring is readily placed and clamped in position and quickly removed after being operated upon.

15 A further object of this invention is the provision of a chuck of this type which is composed of a main attaching member, the gripping end of which is provided with one or more resilient sections having a receptacle 20 so that the bearing ring may be readily clamped therein and at the same time held in a true position.

A still further object of the invention is the provision of means mounted for rotation and for longitudinal movement relative to the main carrying member of the chuck so that the trued ring may be readily removed from the chuck.

In the accompanying drawings:

35 Figure 1 is a side elevation of the complete chuck.

Fig. 2 is an elevation looking from the outer end of the chuck.

Fig. 3 is a section taken on line 3—3 of Fig. 2.

Fig. 4 is a section taken on line 4—4 of Fig. 1.

Referring to the drawings, the numeral 5 designates the main member which as here shown is provided with the attaching threaded portion 6 and with the head 7. This head as here shown is turned to provide the ring receptacle 8 and is further cut by the two partially transverse grooves 9 to provide the 50 clamping member 10. In operation the ring 11 to be trued is fitted within the ring receptacle 8 and the screw 12 is manipulated from the exterior so as to cause the section 10

to be moved and clamp the ring 11, this movement being exceedingly slight but sufficient to maintain the ring 11 in place.

In order to provide a means for quickly releasing the ring or forcing it out of the receptacle 8 and thus facilitating the operation of the present chuck, the member 5 is provided with the external screw threads 13 upon which is mounted the externally milled operating sleeve 14 which in turn is provided with the semi-dovetailed forward edge 15 for the reception of the ring 16, which is non-rotating and carries the releasing pins 17 that are mounted for longitudinal movement in the openings 18 of the head 7, said openings permitting the pins 17 to be projected beyond the base of the receptacle 8 so as to engage the inner edge of the bearing ring 11.

From the foregoing description it is evident that with a chuck of this type the outer ball race ring of a ball bearing is quickly placed in position and clamped therein so as to be maintained true.

In order to prevent the ring or sleeve 14 from rotating and accidentally unseating the ring 11 during the rotation of the chuck, there is provided a longitudinal recess 19 in the inner face of the sleeve 14 adapted for the reception of the spring projected pin 20, mounted in the radial recess 21 of the member 5, as clearly shown in Fig. 3.

What I claim as new is:

1. A chuck, including a main member having an attaching end and a ring receiving receptacle at the opposite end, said receptacle being provided with a clamping portion, means mounted in the receptacle end for acting upon to clamp or release the clamping portion thereof, and manually controlled means mounted for longitudinal movement in the carrying member and for extracting an object seated within the receptacle.

2. A chuck, including a main member having an attaching end and a ring receiving receptacle at the opposite end, said receptacle being provided with a clamping portion, means mounted in the receptacle end for acting upon to clamp or release the clamping portion thereof, manually controlled means mounted for longitudinal movement in the carrying member and for extracting an object seated within the receptacle, and co-

operative means carried by the latter member and the carrying member against accidental movement.

3. A chuck, including a tubular member having an attaching end and a ring receiving receptacle at the opposite end, one section of the wall of the receptacle being spaced from the remaining portion thereof so as to form a clamp, a transversely disposed clamp actuating screw mounted in the member and engaging the clamping portion of the wall to control the movement thereof, and manually controlled means mounted for longitudinal movement in the carrying member and for extracting an object seated within the receptacle.

4. A chuck, including a tubular member having an attaching end and a ring receiving receptacle at the opposite end, one section of the wall of the receptacle being spaced from the remaining portion thereof so as to form a clamp, a transversely disposed clamp actuating screw mounted in the member and engaging the clamping portion of the wall to control the movement thereof, manually controlled means mounted for longitudinal movement in the carrying member and for extracting an object seated within the receptacle, and coöperative means carried by the latter member and the carrying member against accidental movement.

5. A chuck, including a main member having an attaching end and a ring receiving receptacle at the opposite end, said receptacle being provided with a clamping portion, means mounted in the receptacle end for acting upon to clamp or release the clamping portion thereof, said carrying member being provided with external screw threads adjacent the attaching end, an internal screw threaded sleeve mounted thereon, said receptacle end being provided with a plurality of longitudinal openings opening into the receptacle, a pin mounted in each opening for longitudinal movement and a pin carrying member operably connected to the ring whereby the rotation of the ring imparts longitudinal movement to the pin.

50 6. A chuck, including a tubular member having an attaching end and a ring receiving receptacle at the opposite end, one section of the wall of the receptacle being spaced from the remaining portion thereof so as to form a clamp, a transversely disposed clamp actuating screw mounted in the member and engaging the clamping portion of the wall to control the movement

thereof, said carrying member being provided with external screw threads adjacent the attaching end, an internal screw threaded sleeve mounted thereon, said receptacle end being provided with a plurality of longitudinal openings opening into the receptacle, a pin mounted in each opening for longitudinal movement, and a pin carrying member operably connected to the ring whereby the rotation of the ring imparts longitudinal movement to the pin.

7. A chuck, including a tubular member having an attaching end and a ring receiving receptacle at the opposite end, one section of the wall of the receptacle being spaced from the remaining portion thereof so as to form a clamp, a transversely disposed clamp actuating screw mounted in the member and engaging the clamping portion of the wall to control the movement thereof, manually controlled means mounted for longitudinal movement in the carrying member and for extracting an object seated within the receptacle, said carrying member being provided with external screw threads adjacent the attaching end, an internal screw threaded sleeve mounted thereon, said receptacle end being provided with a plurality of longitudinal openings opening into the receptacle, a pin mounted in each opening for longitudinal movement, and a pin carrying member operably connected to the ring whereby the rotation of the ring imparts longitudinal movement to the pin.

8. A chuck, including a main member having an attaching end and a ring receiving receptacle at the opposite end, said receptacle being provided with a clamping portion, means mounted in the receptacle end for acting upon to clamp or release the clamping portion thereof, said carrying member being provided with external screw threads adjacent the attaching end, an internal screw threaded sleeve mounted thereon, said receptacle end being provided with a plurality of longitudinal openings opening into the receptacle, a pin mounted in each opening for longitudinal movement, a pin carrying member operably connected to the ring whereby the rotation of the ring imparts longitudinal movement to the pin, and coöperative means carried by the carrying member and the internally threaded ring for locking the ring and pins against accidental displacement.

In testimony whereof I affix my signature.

JAMES WILSON.
